(57) **CLAIM**

The ornamental design for an antenna for wireless charging, as shown and described.

DESCRIPTION

FIG. 1 is a front, bottom perspective view of an antenna for wireless charging, showing my new design;

FIG. 2 is a front, top perspective view thereof;

FIG. 3 is a front view thereof;

FIG. 4 is a rear view thereof;

FIG. 5 is a bottom view thereof;

FIG. 6 is a top view thereof; and,

FIG. 7 is a right-side view thereof.

The intended use of the design is as an antenna for wirelessly charging electronic devices.
